WITNESS:

UNITED STATES PATENT OFFICE.

JAMES V. VANDAGRIFF, OF WEATHERFORD, TEXAS.

CARD HOLDER.

Application filed November 27, 1922. Serial No. 803,549.

To all whom it may concern:

Be it known that I, JAMES V. VANDAGRIFF, a citizen of the United States, residing at Weatherford, in the county of Parker and State of Texas, have invented new and useful Improvements in Card Holders, of which the following is a specification.

This invention has for its object the provision of a price card holder which is constructed from a single piece of material and given a shape by means of which the holder can be supported upon a shelf beneath the article to be tagged, and provided with means wherein the price tag can be easily associated with the holder or removed therefrom as the occasion requires.

The nature and advantages of the invention will be better understood when the following detailed description is read in connection with the accompanying drawing, the invention residing in the construction, combination, and arrangement of parts as claimed.

In the drawing forming part of this application, like numerals of reference indicate similar parts in the several views, and wherein:

Figure 1 is a perspective view of the card holder.

Figure 2 is a sectional view taken on line 2—2 of Figure 1.

Figure 3 is a sectional view taken on the line 3—3 of Figure 2.

Referring to the drawing in detail, 10 indicates the base of the holder which is adapted to be arranged upon a shelf or other suitable support beneath the articles to be tagged, while 11 indicates the wall of the holder which is vertically disposed and arranged at a right angle to the base 10. The wall 11 is slightly longer than the base 10 and has its ends bent upon itself to provide chan-

nels 12 which receive the ends of the price tag or card indicated by dotted lines at 13. The bent end portions of the wall 11 are arranged in advance and in spaced parallel relation to the wall in the formation of the channels 12. The base 10 is cut away at spaced points as at 14, and the separated portions of the material are then bent upwardly from the point of juncture of the base with the wall 11 to lie in spaced parallel relation to the wall 11. The lower edge of the card 13 is received between these lugs which cooperate with the flanges 12', so that the tag can be easily slipped within the holder or removed therefrom as the occasion may require. The article is very simple in construction, and can be manufactured and sold at a very nominal cost.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

What I claim is:

A card holder formed from a single piece of material and including a base, and a vertically disposed wall arranged at one end of the base, said wall being slightly longer than the width of the base and having its ends bent toward each other and spaced from the wall to provide card receiving channels, and said base being cut away at spaced points to provide bendable lugs, and said lugs being bent upwardly in advance of and in parallelism with said wall to receive and engage the card at points between said channels.

In testimony whereof I affix my signature.
JAMES V. VANDAGRIFF.
